UNITED STATES PATENT OFFICE.

JOHN PERICH, OF LOGAN, WEST VIRGINIA.

COMBINED DOOR LATCH AND LOCK.

1,156,548.

Specification of Letters Patent.

Patented Oct. 12, 1915.

Application filed March 1, 1915. Serial No. 11,189.

To all whom it may concern:

Be it known that I, JOHN PERICH, a subject of the King of Hungary, residing at Logan, in the county of Logan and State of West Virginia, have invented certain new and useful Improvements in Combined Door Latches and Locks, of which the following is a specification.

This invention relates to certain new and useful improvements in combined door latches and locks.

An object of the invention is to provide a lock for doors including a casing for housing the latch and operating mechanism therefor, and also a locking bolt and the operating mechanism for the same.

A further object of the invention is to provide a locking device for doors including a latch mechanism and a lock mechanism, the lock mechanism consisting of a sliding bolt controlled by sliding tumblers whereby the bolt may be held immovable.

With the above general objects in view and others that will appear as the nature of the invention is better understood, the same consists in the novel construction, combination and arrangement of parts to be hereinafter more fully described and then claimed.

In the accompanying drawings which show the preferred embodiment of the present invention and to which reference is had herein by like characters designating corresponding parts throughout the several views:—Figure 1 is a vertical sectional view of a portion of a door with the present lock secured in position, with the face plate removed and part of the elements shown in section, better to illustrate the operation. Fig. 2 is a similar view with the latch and locking bolt in retracted position, and with the tumblers elevated out of contact with the locking bolt. Fig. 3 is an end elevational view of the lock applied to a door, with a part of the door broken away showing the lock mechanism in section. Fig. 4 is a perspective view of the lock casing removed from the door. Fig. 5 is a detail perspective view of the latch. Fig. 6 is a detail perspective view of the locking bolt. Figs. 7 and 8 are detail perspective views respectively, of the latch actuator and the locking bolt actuator, and, Figs. 9 and 10 are detail perspective views respectively, of one of the sliding tumblers and the operating key for the tumblers.

Referring more in detail to the accom-

panying drawings, the reference numeral 15 designates a portion of a door to which the present lock is attached, there being provided the usual escutcheon plates 16 and the face plate 17, while the knobs for operating the latch are designated 18 and the operating knobs for the locking bolt are designated 19.

The lock casing for supporting the lock mechanism is shown in detail in Fig. 4 and includes the face plate 17, the rear wall 20, top and bottom walls 21 and an integral side wall 22. The upper and lower corners of the open side of the casing have enlargements 23, to which a detachable side plate 24 is secured, the casing in its entirety presenting a rectangular frame.

The latch mechanism includes the supporting plate 25 positioned adjacent the upper end of the casing and carries an upstanding angular flange 26 adapted to cooperate with the rear wall 22 to provide a guide for the sliding latch 27. The latch 27 is formed with the usual beveled nose 28 and is provided with a shoulder 29 adapted to engage the rear wall of the face plate 17 to limit its outward movement, there being provided an opening 30 in the face plate to facilitate the passage of the nose therethrough. A pair of communicating openings are provided adjacent the rear end of the latch 27, one extending transversely thereof as at 31, while the other one opens from the top of the latch as at 32. In order to hold the latch normally projected through the face plate opening 30, I have provided the compression coil spring 33 guided at one end by the pin 34 carried by the rear end of the latch 27 while its other end is received over the pin 35 carried by the rear wall 20 of the casing. The member for retracting the latch against the tension of the spring 33 comprises the latch actuator shown in detail in Fig. 7, the same being formed of rectangular end portions 36 adapted to project through aligned openings 37 provided in the side walls 22 and 24 of the casing, while the middle portion thereof is formed cylindrical in cross-section as at 38, and is adapted for positioning within the transverse opening 31 of the latch. A projecting nose 39 is carried by the central cylindrical portion 38 and projects upwardly through the opening 32 of the latch, as clearly shown in Figs. 1 to 3.

When the knobs 18 are oscillated to retract the latch 27, the nose 39 engages the rear wall 40 of the latch opening 32 to move the

same rearwardly against the tension of the spring 33. When the pressure is relieved, the spring will assert its force and restore the latch to its normally projected position.

5 The locking mechanism includes a locking bolt, an actuator, sliding tumblers associated directly with the bolt, and supporting means for the sliding tumblers. A pair of spaced horizontal partition walls 41 extend transversely of the casing and are provided with vertically alined series of openings 42 for the passage of the sliding tumblers 43. Three of these sliding tumblers are provided and carry on one edge thereof adjacent the 10 lower ends and positioned below the lower partition wall 41, projecting lugs 44, the lug 44 carried by the middle tumbler being spaced slightly above the normal horizontal position of the alined lugs of the other two tumblers, these lugs being adapted to be engaged by the wards 45 carried by the key shank 46, it being noted that the middle one of said wards is of slightly increased length 15 relative to the other two, adapted for engaging the elevated middle lug on the central tumbler. The usual form of key-hole opening 47 is provided in the escutcheon plates, the door and the side walls of the casing to facilitate the positioning of the key 46 20 shown in Fig. 10 within the lock.

The locking bolt is shown in detail in Fig. 6 and is designated 48 and the forward portion thereof is provided with a projecting end 49 adapted to be projected through 25 the face plate opening 50, the forward end thereof being supported by the shelf member 51. Additional supporting means for the sliding bolt includes the actuator therefor, the same being shown in detail in Fig. 35 40 48 and comprises ends 52 angular in cross-section and adapted for positioning through alined openings 53 in the side walls 22 and 24 of the casing and are adapted to be received in the operating knobs 19 therefor. 45 The central portion of the locking bolt actuator 52 is formed cylindrical in cross-section as at 54, similar to the latch actuator 36, and this cylindrical portion supports the rear end of the bolt 48, as clearly illustrated 50 in Figs. 1 and 2. A projecting nose portion 55 is carried by the central cylindrical portion 54, and as shown in Fig. 1 is adapted to be received in the recess 56 provided in the under face of the locking bolt 48. The 55 rear end of the bolt 48 is provided with a series of sockets 57 into which are received

the lower ends 58 of the sliding tumblers 53, and in such position, the bolt 48 is held in locked projected position. In order to retract the same, it is necessary that the tumblers 43 be elevated to remove the lower ends thereof from the sockets 57 whereupon the knob 19 may be rotated to cause the finger 55 to engage either of the end walls of the recess 56 in the bolt to shift the same to retracted position.

It is to be noted that the latch is independently operated from the lock and that a single casing incloses both mechanisms while the construction of the locking bolt 48 is extremely simple in operation and effective in use. The bolt 48 is retracted in the manner as above stated after the lower ends 58 are removed from the sockets 57, such removal being caused by the locking key 46 with the central relatively long ward 45 70 engaging the elevated lug 44 on the middle tumbler while the shorter wards 45 engage 75 the lower lugs on the end tumblers.

80 From the above detailed description of the invention, it is believed that the operation will be readily apparent, and while I have shown and described the preferred embodiment of the present invention, I do not wish to confine myself to the exact details of construction shown, as various forms, modifications and arrangements of the parts as shown may be had without departing from the spirit and scope of the invention as 85 claimed.

86 What I claim as new is:—

A device of the class described, comprising a casing, a locking bolt slidably mounted within said casing provided with a single 95 slot extending from side to side thereof, vertically sliding tumblers adapted to having their lower ends engaged in the single slot, and interlock with said bolt and being arranged in parallelism, lugs carried by said tumblers and being arranged in different horizontal planes, and a key having wards of different lengths adapted to engage said lugs to simultaneously remove the tumblers from engagement with the bolt.

100 105 In testimony whereof I affix my signature in presence of two witnesses.

JOHN PERICH.
